CLAIM

The ornamental design for a pair of removable attachment caps for the body of a smart watch, as shown and described.

DESCRIPTION

This application is related to application Ser. No. 29/635,224 filed Jan. 29, 2018, which is incorporated entirely by reference herein for all purposes.

FIG. 1 is a top, front, right side isometric view of a pair of removable attachment caps for the body of a smart watch, shown exploded from the body of a smartwatch showing our new design.

FIG. 2 is a right side elevation view of FIG. 1.

FIG. 3 is a left side elevation view of FIG. 1.

FIG. 4 front side elevation view of FIG. 1, with attachment caps displaced sideways for visibility.

FIG. 5 is a back side elevation view of FIG. 4.

FIG. 6 is a top plan view of FIG. 4.

FIG. 7 is a bottom plan view of FIG. 4.

FIG. 8 is a bottom, left side isometric view of FIG. 4.

FIG. 9 is a front isometric view of one of the end caps of FIG. 1.

FIG. 10 is a front elevation view of FIG. 9.

FIG. 11 is a back side elevation view of FIG. 9.

FIG. 12 is a left side elevation view of FIG. 9.

FIG. 13 is a right side elevation view of FIG. 9.

FIG. 14 is a top plan view of FIG. 9.

FIG. 15 is a bottom plan view of FIG. 9.

FIG. 16 is a front bottom isometric view of FIG. 9.

FIG. 17 is a cross-sectional view taken along line 17-17 of FIG. 9 directionally upward.

FIG. 18 is a cross-sectional view taken along line 18-18 of FIG. 9 directionally downward; and,

FIG. 19 is a cross-sectional view taken along line 19-19 of FIG. 9.

The features shown in broken line in the drawings depict environmental subject matter only and form no part of the claimed design.
